Franklin R. Mathews and Harold L. Blanton,
Washington, D. C.

Application June 25, 1947, Serial No. 139,900

Term of patent 3½ years

(Cl. D36—8)

To all whom it may concern:

Be it known that we, Franklin R. Mathews and Harold L. Blanton, citizens of the United States of America, and residents of Washington, District of Columbia, have invented a new, original, and ornamental Design for a Drinking Glass, of which the following is a specification, reference being had to the accompanying drawing, forming part thereof, in which

Figure 1 is a front view of a drinking glass, showing our new design;

Figure 2 is a side view;

Figure 3 is a rear view; and

Figure 4 is a perspective view thereof.

We claim:

The ornamental design for a drinking glass, as shown.

FRANKLIN R. MATHEWS.
HAROLD L. BLANTON.
